R. C. STUBBS.
CONCRETE CLEANER.
APPLICATION FILED AUG. 28, 1916.

1,214,093.

Patented Jan. 30, 1917.

UNITED STATES PATENT OFFICE.

ROBERT C. STUBBS, OF DALLAS, TEXAS.

CONCRETE-CLEANER.

1,214,093.

Specification of Letters Patent. Patented Jan. 30, 1917.

Application filed August 28, 1916. Serial No. 117,144.

To all whom it may concern:

Be it known that I, ROBERT C. STUBBS, a citizen of the United States, residing at Dallas, in the county of Dallas and State of Texas, have invented certain new and useful Improvements in Concrete-Cleaners, of which the following is a specification.

My invention relates to a concrete cleaning machine, and particularly to machines provided with cleaning devices to be operated at high speed when moved over the concrete, and the object is to provide a device for cleaning dirt, dust and mortar coating from fresh laid concrete, that is, concrete which has been laid and set and which has a rough surface ready to receive a wearing coat of adhering material. In order that the adhering material shall be firmly and permanently set on the concrete, all the dirt and mortar coating, and even the dust, must be taken from the rough concrete. For this purpose a cleaning device must be used which has a constant high speed and it is necessary to transport such cleaning device over the surface with some slow moving truck which can be moved at any speed desirable and in any direction desirable. Some portions of the concrete will need more scrubbing than other portions and for this reason, the truck can be moved at a low speed and a higher speed whenever desired, but the cleaning device must run at a constant high rate of speed.

The object is to provide a revolving cleaner which is provided with spring steel, highly flexible and resilient cleaning brushes which can be readily adjusted relative to the surface to be cleaned.

Other objects and advantages will be fully explained in the following description and the invention will be more particularly pointed out in the claims.

Reference is had to the accompanying drawings which form a part of this application.

Figure 1 is a perspective view of the machine. Fig. 2 is a side elevation of the supporting wheel and the adjusting mechanism. Fig. 3 is a rear elevation of the adjusting mechanism. Fig. 4 is a similar view to Fig. 3, but showing the adjusting frame in section. Fig. 5 is a detail view of the revolving broom, showing the drum and part of the spring steel brushes.

Similar characters of reference are used

to indicate the same parts throughout the several views.

The improved cleaner is provided with a deck or platform 1 on which is mounted a motor 2 which may be of any suitable size. The motor 2 is held on the deck 1 by a frame 3. The deck 1 is supported on braces 5 which are attached to the deck 1. The braces 5, each consist of a single bar of iron having inclined portions extending up to the deck 1 and a horizontal portion 6, carrying bearing 7 for the shaft 8 of the brush drum 9. The deck 1 is further supported by a standard or rear support 10 which is bolted to the deck 1. The support 10 is provided with a roller 11. The standard 10 is curved for the purpose hereinafter explained. Brackets 12 are riveted rigidly to the braces 5 near the front of the machine. A swinging frame, composed of side arms 13 and 14 and rear bar 15, is connected to the brackets 12 by pivot bolts 16 so that the front part of the deck 1 is supported on the pivot bolts 16. The frame pieces 13 and 14 are supported by the wheels 17 and 18 which should be ball bearing wheels. Spindles 19 are bolted rigidly to the frame pieces 13 and 14 for the wheels 17 and 18. The weight of the deck 1 with the propelling motor 2 bearing down on the front of the frame pieces 13 and 14 would tend to elevate the rear ends of these frame pieces with the cross-bar 15. If not otherwise checked, the frame piece 15 will be stopped by the curved portion of the support 10. A trip 20 is pivotally connected with the standard 10 and operates in a slot 21 which is made in this support. A spiral spring 21 is attached to support 10 and to the trip 20 and tends to draw the upper part of trip 20 forward and to cause the lower part to bear against the bar 15. The trip 20 has a shoulder 22 which is adapted to engage the upper edge of the bar 15. A foot piece or bearing 23 is attached to bar 15. When the broom is to be brought out of operative position, press down on the bearing 23 until the shoulder 22 will catch on top of bar 15. The spring 21 will cause the shoulder 22 to snap over the top of the bar 15 and thus hold the rear end of the swinging frame down while the broom is not operating. The shoulder 22 will prevent the rear end of the frame from rising and so hold the broom up out of operative position. To release the bar 15 from the shoulder 22, raise

the trip 20 until the shoulder 22 slips off of the bar 15. The front part of the frame will be forced down by the weight of the broom and the deck and engine because the 5 weight will be exerted on the pivot bolts 16 which are forward of the spindles 19 of the supporting wheels 17 and 18.

In order to prevent the broom from dropping too low and pressing too hard on 10 the pavement while revolving, stops 24 are provided to limit the upward motion of the rear end of the adjusting frame. Hangers 25 are attached to braces 5 and a plurality of holes made in the hangers 25 so that the 15 stops 24 can be inserted at the proper positions to secure the desired pressure of the brushes against the concrete. The wheels 17 and 18 support the broom but have nothing to do with driving the broom. The 20 broom is driven by the motor 2. A sprocket wheel 26 is mounted rigidly on the broom shaft 8 and is driven by a sprocket chain 27 which is driven by a sprocket wheel 28 which is rigid with a counter shaft 29. The 25 shaft 29 is driven by gearing from shaft 4 of the motor 2. A sprocket wheel 31 is rigid with shaft 4 and drives a sprocket chain 30 which drives shaft 29. A belt 32 drives a fan 33 from the shaft 29. The 30 broom is made up of a drum 9 (which may be of wood) and steel brushes 34. These brushes may be made of steel but may be made of other material and must be flexible and highly resilient. They must not only 35 brush material away but must loosen the material and brush the loosened material away. Vanes or dust guards 35 are provided to prevent the dirt and dust and other material from being thrown on the 40 ground or surface already cleaned. A standard 36 is pivotally mounted on the deck 1 by means of brackets 37 and this standard has an arm 37 which is riveted to the vane 37. The vane can thus be shifted 45 from one side to the other of the machine to prevent the dirt and other matter from being thrown to one side on the concrete already cleaned. A clutch 38 is provided for throwing the broom into or out of working 50 condition.

The operator uses the machine by pushing the machine along on the surface while the motor is driving the broom. A hand rail 38 is secured to the deck 1 and the operator pushes the machine along as slowly 55 or as fast as may be necessary, but the speed of locomotion of the machine does not affect the speed of the broom which is being driven by the motor.

60 What I claim is.

1. A concrete cleaner comprising a deck, a high speed motor mounted on said deck,

bearing frames attached to said deck, a revoluble cleaner journaled in said frames, gearing operatively connecting said cleaner 65 and said motor, a swinging frame pivotally connected to said bearing frame, supporting wheels journaled on said swinging frame and operating independently of said motor and revoluble cleaner, and means for 70 adjusting said revoluble cleaner relative to said swinging frame.

2. A concrete cleaner comprising a deck, a high speed motor mounted on said deck, bearing frames attached to said deck, a 75 revoluble cleaner journaled in said frames, gearing operatively connecting said cleaner and said motor, a wheeled support for one end of said deck, a swinging frame pivotally connected to said bearing frames, supporting wheels journaled on said swinging frame and operating independently of said 80 motor and revoluble cleaner, and means for adjusting said revoluble cleaner relative to said swinging frame.

3. A concrete cleaner comprising a vertically adjustable deck, bearing frames attached to said deck, a revoluble cleaner journaled in said bearing frames, a high speed motor mounted on said deck and operatively connected with said cleaner, a wheeled support for one end of said deck, a swinging frame pivotally connected to said bearing frames at one end and adjustably connected to said wheeled support and supporting wheels journaled on said swinging frame, said motor and cleaner operating independently of said supporting wheels.

4. A concrete cleaner comprising a deck, a wheel support for one end of said deck, a 100 swinging frame operatively connected to the other end of said deck, means for adjusting said swinging frame relative to said wheel support, supporting wheels journaled on said swinging frame, a revoluble cleaner 105 journaled on said deck, a high speed motor mounted on said deck for driving said cleaner independently of said supporting wheels.

5. A concrete cleaner comprising a deck, 110 a wheeled support for one end of said deck, bearing frames attached to said deck, a revoluble cleaner journaled in bearings supported by the bearing frames, a swinging frame operatively connected to said bearing frames and adjustably connected to said wheeled support, supporting wheels journaled on said swinging frame, means mounted on said deck for driving said 115 drum and means for adjusting said swinging frame relative to said wheeled support.

In testimony whereof, I set my hand, this 17th day of August, 1916.

ROBERT C. STUBBS.
